Term of patent 7 years

(Cl. D71—1)

FIG. 1.

FIG. 2.

FIG. 3.

FIG. 4.

Figure 1 is a perspective view of a combined trailer and raft, embodying my new design, illustrated in position for use as a trailer.

Figure 4 is a perspective view of a modified form of my combined trailer and raft as shown in Figs. 1, 2, and 3.

I claim:

The ornamental design for a combined trailer and raft, as shown and described.
